[57] CLAIM

The ornamental design for a combination beam and cable clamp, as shown and described.

DESCRIPTION

FIG. 1 is a perspective view of my combined beam clamp and cable clamp, with the beam and cable being shown in phantom view;

FIG. 2 is a plan view thereof;

FIG. 3 is a side elevational view thereof, the other side being a reverse image thereof;

FIG. 4 is a front elevational view thereof;

FIG. 5 is a rear elevational view thereof; and,

FIG. 6 is a bottom view thereof.

The broken lines showing a beam and a cable in FIG. 1 are for illustrative purposes only and do not form part of the claimed design.
